ELECTRICAL CONNECTER

Joseph Wertzheiser, Newark, N. J., assignor to
Hatfield Wire & Cable Co., Hillside, N. J.

Application May 23, 1935, Serial No. 22,944

12 Claims. (Cl. 173—332)

This invention relates to an electrical connector especially adapted for use in connection with flat irons or heating devices having contacts of the type such as are now ordinarily used on electric flat irons.

In electrical connectors of the type described, the device is usually made of two parts of suitable insulating material and various means have heretofore been proposed and used for holding these insulating parts together. Some of the earlier devices used machine screws and nuts, while later devices have utilized various types of external spring clips spanning both members. The first type has certain objections, one of which is that the nuts become loosened and the parts separate or fall apart entirely. In the external spring clip type of fastening means, the springs are accidentally hit and knocked off the connector, allowing the pieces to fall apart. Furthermore, with the exterior type of spring clip, as the flat iron is heated up in use, the heat is conveyed to the connector and the spring clips actually get hot enough to burn the fingers of an operator when pulling the connector from the iron.

It is one of the objects of my present invention to provide a fastening means which is normally positioned within the confines or interior portions of the insulating parts, so that it or they cannot be accidentally knocked out of place, and at the same time eliminates the possibility of burned fingers on the hand of the operator. Since the fastening means are encompassed within the parts of the connector, the exterior appearance of the connector is enhanced.

Another object of my invention is to provide an electrical connector which is cheap to manufacture and one that is easily assembled and disassembled, yet when in assembled condition, the parts are securely held in operative position.

My improved construction will be readily understood by reference to the annexed drawing, wherein:

Figure 1 is a plan view, approximately twice the size, of the connector in assembled condition, without the connecting cord.

Figure 2 is a section on the line 2—2 of Figure 1.

Figure 3 is a view of the terminal or contact end of the connector.

Figure 4 is a partial, sectional view of the lower portion of Figure 2, but on a scale twice the size of Figure 2, showing the clamping device in four stages of its assembly.

Figure 5 is a view approximately four times the

size of the clamping device for holding the insulating parts together.

In the different views, 1 and 2 are members of suitable insulating material which, for low cost in manufacture, are preferably made substantially identical or symmetrical, thereby comprising two complementary cooperative parts. The insulating parts 1 and 2 may have various outside design features which, however, are not the subject matter of the present application. The parts 1 and 2 have recesses 3, 4 and 5 at the top portions to receive the usual guard spring around the cord carrying the electrical conductors to the contact members 6 and 7 which are positioned in lateral spaced relation in the lower portion of the connector. The contact parts 6 and 7 are usually made of two pieces formed and positioned within the parts 1 and 2 so as to flexibly engage the contact prongs on the flat iron. The contact parts 6 and 7 are usually fastened together at their inner ends by a clamping screw (not shown) which also acts to clamp the conductor to the terminals. The flexibility at the exterior end of the contact parts 6 and 7 may be attained in several ways. First, by having sufficient clearance space around the contact parts 6 and 7 so that they will spread sufficiently without engaging the interior parts of the insulators in which they are carried as the connector is pushed over the contact prongs of the iron. Another way is to hold the contact parts 6 and 7 closely together by the material of the pieces 1 and 2, and allow the parts 1 and 2 to spread under the tension of the spring-holding clamps. My invention can be applied to either type of construction.

In my improved means for holding the parts 1 and 2 securely together, I have provided a clamp 8, shown in Figure 5, which has an eye portion 9 extending into hook-shaped arms 10 and 11, thereby forming a tong-like shaped clamp. The member 8 is made of a material which is capable of taking and retaining a spring tension. I prefer to use two of the clamps 8, and in order to get them into normal locking position as shown in Figure 2, I have provided each of the parts 1 and 2 with transverse orifices or port holes 12 and interior spaces 13; that is to say, the spaces 13 are within the material of the insulators 1 and 2, being below the outer surfaces or confines thereof. The interior of the members 1 and 2 is provided with portions 14 which help form part of the orifices 12. The parts 14 have formations or surfaces 15, 16 and 17 which act in the nature of cam surfaces, over

which one end, for example 11, of the clamp 8 is adapted to ride when the clamp 8 is forced into locking position.

The various steps assumed by the clamp 8 are outlined in Figure 4. The clamp is first placed in the position shown by the dotted lines a, wherein the end 11 of the clamp engages the cam surface 15. On pressure being applied to the clamp 8, it takes up the position b, in which the eye portion 9 rides on the surface 18 forming the outer surface of the orifices 12, and the portion 11 then passes to the cam surface 16. Continued pressure on the clamp 8 moves it to the position c, in which the end 11 is just passing over the cam surface 17. Due to the eye portion 9 engaging the surface 18 and the portion 11 of the clamp engaging the cam surfaces as above described, the clamp 8 is spread and put under increasing tension so that immediately after the end 11 passes over the cam surface 17, it will snap into the position d shown in full lines, wherein the hook-shaped ends 10 and 11 snap over the recessed formations 19 as shown in Figure 2.

From this construction, it will be seen that the clamps 8 are substantially positioned within the interior of the insulating members 1 and 2, so that they cannot be accidentally hit and knocked out of position. I prefer to use two of the clamps 8 as shown in Figure 2, located in reverse position; that is to say, with the hook ends 10 and 11 presented toward each other, but in longitudinal spaced arrangement substantially on the median line of the connector. When it is desired to take the connector apart, the clamps 8 may be reached through the transverse orifices 12 and either pushed, by means of the eyelet portion 9, into reverse direction to the various positions c, b, a, shown in Figure 4; or, as I prefer, by placing a suitable tool, such as a screw driver, at the point 20 and pulling the end 11 around the cam surfaces in the reverse order indicated.

Since the parts 1 and 2 are moulded in a suitable die, the cam surfaces 15, 16 and 17 and the locking formation 19 are easily secured. The parts 1 and 2 may also be provided with recesses 21 to receive a dowel pin so the parts 1 and 2 may be more easily assembled and insured against mis-alignment.

Since the clamps 8 are inexpensive to manufacture, I prefer to use two of them in the manner indicated, although one will hold the parts together very securely. Because the clamps 8 are housed within the insulating parts 1 and 2 of the connector, they cannot be accidentally moved out of position or cause any burns to the fingers of the operator, and even if the clamps should become so hot as to lose their temper, a hardly probable case, they would not drop out because the portion 9 striking on the surface 18 would prevent their turning sufficiently of themselves to allow them to pass out of the port holes 12. It will be observed from the drawing and from what has been said, that the eye portion 9 of the clamp 8, wherein resides the greater portion of the tension of the clamp, when in locking position, as shown in full lines in Figure 4 and also in Figure 2, is free from contact with the surface 18, and being thus situated in the transverse orifice 12, is subject to the cooling effects of air currents passing through this orifice. It is further to be noted that the clamps 8, in locking position, only make contact with the material of the plug over about one-half of their interior surfaces, which tends to keep down the

amount of heat which the clamps pick up by direct contact with the material of the plug.

While I have shown a preferred way of making the clamps 8, the shape may be varied, as well as the cooperative formations of the parts 1 and 2.

What I claim is:

1. An electric connector including a pair of complementary insulating members having certain interior recesses to receive contact members 10 and having a pair of spaced transverse openings through said insulating members, parts below the outer surface of said insulated members adjacent said openings being formed to assist in the insertion and holding of clamps, and spring 15 clamps formed to cooperate with said parts to engage the same to clamp said insulating members together.

2. An electric connector including a pair of complementary insulating members having certain interior recesses to receive contact members and having a pair of spaced transverse openings through said insulating members located substantially on the median line of the connector, and a pair of spring clamps insertable 25 through said openings and engaging locking portions in said insulating members, said locking portions being below the outer surface sufficiently so the clamps, when in locking position, are also below the outer surface of said insulating members.

3. An electric connector including a pair of complementary insulating members having certain interior recesses to receive contact members, spring clamps located within the confines of said 35 insulating members for clamping said members together, said members having spaces and orifices starting from within and leading to their exterior for passing said clamps into clamping position.

4. An electric connector including a pair of complementary insulating members having certain interior recesses to receive contact members, a pair of spring clamps inversely positioned in spaced relation within the confines of said 45 insulating members and engaging formations below the outer surface of said members for clamping the members together, said members having spaces and orifices leading to said formations for passing said clamps into clamping position. 50

5. An electric connector including a pair of complementary insulating members having certain interior recesses to receive contact members, at least one spring clamp located entirely within the confines of said insulating members for 55 clamping them together, at least one of said members having an exterior orifice therein leading into the interior of said members, said orifice serving as the means for passing said clamp into its clamping position and also for withdrawing the clamp.

6. An electric connector including a pair of complementary insulating members having certain interior recesses to receive contact members, spring clamps having an eye portion extending into hook-shaped arms, said clamps being positioned in spaced relation entirely within the confines of said members with the hook-shaped arms embracing enlargements below the surface 70 of said members to hold said members together, said members having transverse orifices for passing the clamps from either side of the connector into their clamping position, the eye portions of said clamps being reachable from the exterior 75

through said orifices to force them from clamping position.

7. A connector as set forth in claim 6, further characterized in that the surfaces of said enlargements form parts of said transverse orifices and have cam surfaces which cooperate with the opposite sides of said orifices to set the clamps under tension to cause them to snap into place when they are forced toward locking position.

10 8. An electrical connector including a pair of separable insulating members, metallic contact parts housed in lateral spaced relation within said members, a pair of spring clamps spaced longitudinally below the outer surface of the connector and between said contact parts, said insulating members having formations below their outer surfaces to receive the clamps to hold said members together, said members having transverse orifices and spaces below their outer surfaces leading to said formations whereby the clamps may be passed into or withdrawn from clamping position.

9. An electrical connector including a pair of separable members of insulating material having certain interior recesses to receive contact members, each of said insulating members having at least one transverse port hole arranged to align with the port hole in the other insulating member when the insulating members are in assembled position, each of said insulating members having a recess opening into its port hole, the walls of parts of said recesses and port holes having formations to cooperate with a spring clamp and a spring-clamp formed to cooperate

with said recess walls to engage the same to clamp said insulating members together.

10. A connector as set forth in claim 9, further characterized in that the port holes are dimensioned so as to at least assist in putting the clamp under tension as it is forced into locking position as well as to prevent the clamp from falling out of the connector should it lose its tension.

11. A connector as set forth in claim 9, further characterized in that the port holes are dimensioned so as to at least assist in putting the clamp under tension as it is forced to locking position, but to leave the tension end of the clamp free from contact with the wall of the port hole after the clamp is moved to locking position.

12. An electrical connector including a pair of separable insulating members, metallic contact parts housed in lateral spaced relation within said members, at least one spring clamp spaced entirely within the confines of the connector members, which have formations well below the outer surface thereof to receive said clamp to hold said members together, said members having port holes forming a transverse orifice when the insulating members are together, said insulating members also having spaces leading to said formations whereby the clamp may be passed into or withdrawn from clamping position, only a portion of the clamp being in actual contact with the said formations, the tension end of the clamp being freely positioned in said transverse orifice for the purpose described.
